UNITED STATES PATENT OFFICE

JOHN H. McGEHEE, OF SACRAMENTO, CALIFORNIA

COUPON FILING AND CANCELING DEVICE

Application filed August 27, 1927. Serial No. 215,948.

My invention relates to improvements in coupon filing and canceling devices, and it consists in the combinations, constructions, and arrangements hereinafter described and 5 claimed.

An object of my invention is to provide a coupon filing and canceling device which has novel means for retaining differently numbered coupons in prearranged piles, access 10 being had to the coupons of the various piles so that new ones may be added until the piles are complete, whereupon a canceling device is employed for puncturing all of the coupons in a pile, and for preventing the removal of coupons after they have been canceled, without detection.

A further object of my invention is to provide a device of the type described, in which the various piles of coupons are 20 yieldingly held in contact with each other by a spring presser arm of novel construction, this arm being swingable into inoperative position and being automatically retained in this position until the operator 25 wishes to again release the arm.

A further object of my invention is to provide a device of the type described, in which a sealing device is provided for sealing the containers holding the coupons after 30 the same have been canceled, or prior to cancellation, if it is desired to shift the coupons from one place to another while still uncanceled.

Other objects and advantages will appear 35 in the following specification, and the novel features of my invention will be particularly pointed out in the appended claims.

My invention is illustrated in the accompanying drawings, forming a part of this 40 application, in which:

Figure 1 is a perspective view of a compartment designed for holding coupons;

Figure 2 is a section along the line 2—2 of Figure 1;

Figure 3 is a side elevation of one row of coupon-retaining compartments;

Figure 4 is a perspective view of a container designed for holding a number of rows of compartments; and

Figure 5 is a portion of a data sheet em-

ployed for determining the number of coupons in a compartment, and what particular coupon or coupons is missing.

In carrying out my invention I provide a number of tills "1" having rows of compartments "2" formed therein, see Figure 3. In the present form of the device I provide five compartments 2 in each row, although any number can be employed without departing from the spirit and scope of my 60 invention.

Each compartment is identical and therefore a description of one will suffice for a description of all.

Reference to Figure 1 shows a perspective 65 view of one of the compartments, and it will be noted from this figure that the compartments are each formed of a single strip of material stamped and cut in the manner shown. The compartments have a base 70 plate 3, end walls 4 and side retaining members 5. The base 3 is of the same size as the coupon 6. Note the coupons in Figure 3. The retaining members 5 have a width equal to one-third the distance of the length of a 75 compartment. This construction is designed in such a manner as to permit a finger to be inserted between the retaining members 5 and end walls 4 when it is desired to remove coupons from the compartment, or add coupons to the compartment, or to check the 80 number on and amount of the individual coupons. The tops of the retaining members 5 are bifurcated and the upper ends are curled or rounded in the manner shown at 7. 85

The cross portions formed in this manner are aligned as to height with projections 8 struck inwardly from the end walls 4. The portions 7 and the projections 8 aid in retaining the coupons in place. The end walls 4 are formed by bending the strip of material back upon itself, as shown, the walls being provided with a cylindrical portion 9 at the top thereof, and with lugs 10 that are bent around the opposite side of the wall 95 for holding the two thicknesses of the wall together, as shown in Figure 1.

Each compartment is provided with a coupon presser arm 11, which is yieldingly held against the uppermost coupon by a 100

spring 12. Figure 2 clearly shows how the spring 12 is mounted upon a rod 13, which in turn is journaled in the cylindrical portion 9 of the end walls 4. The presser arm 5 is journaled on the rod 13 and the spring has one end mounted in the cylindrical member 9 at 14 and its other end bearing against the presser arm 11 at 15.

It will be noted from Figures 1 and 2 that 10 the cylindrical portion 9 has a notch 16 therein for receiving one edge of the presser arm 11, when the arm is swung into inoperative position, as indicated by the dotted lines in Figure 3. The spring 12 performs the 15 double function of urging the arm 11 downwardly upon the coupons and also of holding the arm in the notch 16 when the arm is in inoperative position, whereby it is prevented from being swung downwardly. In 20 the first instance the spring 12 acts as a torsional spring and in the second instance it acts as a compression spring.

The coupons may be temporarily placed 25 in the compartments 2, and when a predetermined number have been placed in any one of the compartments, the coupons in that compartment are removed and a canceling member 17 is then bent upwardly from the bottom 3 into the dotted line position shown 30 in Figure 1. The coupons are then replaced in the compartment, and during the latter operation the coupons are punctured.

The canceling member 17 is also shown in 35 Figure 3, where it will be noted that it punctures all of the coupons in the compartment when the bunch of coupons are forced into the compartment over the canceling member, which is pointed for this purpose. The sheet-metal blank from which the compartments 40 are made is so thin that the canceling member 17 is bendable by means of the fingers, and may be bent up or down as desired.

After all of the coupons of a given till 1 have been disposed in place and have been 45 canceled, a seal in the form of a plate 18 is extended over the tops of the compartments 2, and has flanges 19 at the ends thereof for engaging with the end walls of the till. A seal consisting of a wire 20, and a lead piece 50 21 soldered to the wire is passed through openings in the plate 18 and the end walls of the row at each end of the till. In this way the row is sealed and the coupons cannot be 55 tampered with without detection. If desired, designating slips 22, see Figure 4, may be pasted upon the plate 18 over each compartment for indicating the numbers of coupons in the particular compartment there-beneath.

60 In Figure 4 I show a container 23 which is large enough to hold eight tills 1. Eight rows will provide forty (40) compartments. If desired, the container may be made of a smaller size or a larger size, or may be dis- 65 pensed with and the tills after being sealed

in the manner already described may be placed in a vault or other place of safe keeping. On the inside of the cover 24 of the container 23 I mount a data chart 25. A portion of this chart is shown in Figure 5. The chart is provided with a number of rectangles 26 corresponding to the number of compartments 2. Each rectangle is again divided into one hundred (100) squares, and these squares are numbered from one to one hundred.

As the coupons come in, they are placed 70 in their respective compartments and then a line indicated by 27 is drawn through the number on the chart 25, corresponding to the number of the coupon. In this way the person can instantly tell the number of coupons in any compartment and exactly what coupons are missing. The container 23 may be sealed by passing a sealing device, not shown, through lugs 28 when the cover is swung into closed position.

Although I have shown and described one embodiment of my invention, it is to be understood that the same is susceptible of various changes and I reserve the right to employ such changes as may come within the scope of the appended claims.

I claim:

1. A device of the type described comprising a till having a plurality of coupon-receiving compartments, a canceling member carried by each compartment and being manually movable into operative or inoperative position, a closure for said till and extending over the tops of all the compartments, and means for sealing the closure to the till.

2. A coupon filing and canceling device comprising a till having a plurality of coupon-receiving compartments, each compartment having a base and end walls, the sides of said compartments being open the greater part of their lengths for permitting access to the coupons, a spring arm for each compartment for holding the coupons in place, means for holding the arm in inoperative position for permitting the removal of the coupons, and a canceling member carried by the base of each compartment and being bendable into operative or inoperative positions.

3. A coupon filing and canceling device comprising a plurality of tills, each till having a plurality of coupon-receiving compartments, a canceling member carried by each compartment and normally being disposed in inoperative position, said member being bendable into operative position, and a closure for each till extending over all of the compartments in the till.

4. A coupon filing device comprising a plurality of tills, each till having a plurality of compartments for receiving coupons, a closure for each till adapted to be disposed

over the tops of all the compartments in the till, means for sealing the closure to the till, and a chart for recording the coupons thereon as they are placed in the compartments, 5 whereby the filed coupons may be readily determined.

5. A till fashioned from a single strip of material and including a plurality of compartments formed by bending the material 10 into a bottom and end walls, the end walls of one compartment being abutted against the end walls of the adjacent compartments, and projections extending from the wall of one compartment and clamping around the 15 wall of the adjacent compartment.

6. A till fashioned from a single strip of material and including a plurality of compartments formed by bending the material into a bottom and end walls, the end 20 walls of one compartment being abutted against the end wall of the adjacent compartment, and side walls integral with the bottom of each compartment.

7. A coupon filing device comprising a 25 plurality of tills, each till having a plurality of compartments for receiving coupons, a closure for each till adapted to be disposed over the tops of all of the compartments in the till, and a chart for recording the 30 coupons thereon as they are placed in the compartments, whereby the filed coupons may be readily determined.

JOHN H. McGEHEE.
